SECTIONAL FURNACE

Allen P. Livar, Yonkers, N. Y., assignor to Reynolds Corporation, New York, N. Y., a corporation of Delaware

Application September 21, 1936, Serial No. 101,862

1 Claim. (Cl. 126—110)

This invention relates to air heating furnaces of the sectional type and is more particularly directed to an improved section structure.

Furnaces of the general type to which this invention pertains have been used for the heating of air, and it is relatively common practice to form sections such that upon assembly of a plurality of similar parts there will be formed a continuous combustion chamber and a continuous flue defined by cooperating openings in each of the several parts of the furnace together with a heat exchange region comprised by the hollow body portions of the sections. Such prior structures have been found to be poorly adapted for the construction of small, compact domestic air conditioning units since they were formed with heat exchange portions of considerable length in order to provide sufficient heat transfer area in the streams of air in the furnace.

These difficulties are obviated in the present invention by the provision of flat enclosed heat exchange portions in each of the sections. The sections are of unusual width, but it has been found that adequate contact of hot gases of combustion with the interior surfaces of the section and efficient heat transfer from the outer surface to the air to be heated is obtained by the provision of gas directing and heat exchanging fins.

The present invention therefore contemplates an improved section for such furnaces by means of which efficient heating is accomplished in a unit of novel and improved design.

The above and other objects which will be evident as the description proceeds, will be best understood by referring to the following detailed description and accompanying drawings forming a part thereof in which

Figure 1 is a perspective view illustrating the system substantially in a typical installation within a conventional cellar of a dwelling house;

Figure 2 is an enlarged fragmentary perspective of the air conditioning unit, with the cabinet thereof being broken away for convenience to illustrate the direction of air passage therein and the location of the air conditioning equipment with respect to the air passage;

Figure 3 is a side elevation of a typical three-section assembly of heating unit constituting one typical embodiment of the invention as viewed from the left of Figure 2 and within the cabinet, one clean-out aperture closure being shown removed;

Figure 4 is a detailed view showing, in perspective, the construction of the closure plate for

baffle clean-out aperture at the edge of each section;

Figure 5 is a fragmentary section taken on the line 5—5 of Figure 3;

Figure 6 is a longitudinal section taken on the line 6—6 of Figure 5;

Figure 7 is a transverse section taken on the line 7—7 of Figure 3;

Figure 8 is a view corresponding to Figure 7 and showing a modified arrangement of interior baffles;

Figure 9 is an exploded perspective view generally from the rear of the cabinet and illustrating the details of its construction and method of assembly; and

Figure 10 is a view on reduced scale illustrating a modification of the cabinet appropriate for heating units of one or two sections therein, wherein it will be observed that the rear of the heating unit is connected through the side of the cabinet.

Referring to the drawings in detail, a typical installation of an air conditioning system embodying the invention is shown located in the cellar of any conventional dwelling adjacent an end wall 11 thereof. It will be understood that the location shown is not essential, it being entirely practicable to locate the system as convenient in order to conform with architectural or other requirements. This system includes an air conditioning unit 12 connected at one side thereof to supply various portions of the structure with conditioned air through a conduit system 13. Conduit system 13 comprises inter-connected conduit members pre-fabricated, under standardized mass production conditions, at the factory and assembled of any desired combination of straight runs 14, curves 15, and fixed or variable split off elements 16 communicating with any suitable passages 17 through the walls or flooring (not shown) of the building. The conduit sections are specifically designed to provide the proper conducting capacity while enabling a maximum head clearance, in that the most capacious or deepest member extends not more than any desired distance, such as 8 inches, from the ceiling. Any suitable tie or bracket members (not shown) connected in the building structure may be employed for supporting the various portions of the conduit system. In its preferred embodiment the invention contemplates the air conditioning system to be of the re-circulating type in which case it will be observed that the conduit system includes any requisite arrangement of return conduit elements 18, also pre-

fabricated and standardized at the factory, and communicating with the opposite side of the air conditioning unit 12.

An integral element of the air conditioning system is a cabinet 18 (Fig. 2) communicating with the conduit system 13. Cabinet 18 is preferably rectangular and is entirely pre-fabricated in that it can be readily assembled in situ or demounted by any workman. The plan of the cabinet is defined by a rectangular bottom frame member 20 including opposed side and end angle members 21 and subdivided approximately into halves by transverse angle member 22 welded therein. It will be understood that the angle members 21 and 22 are disposed with an upwardly extending edge so that the opposite surface coincides with the floor. Cabinet 18 includes opposed front and back walls or plates 23 and 24 respectively, and opposed end plates 25 and 26. These plates are composed of sheet metal and front and back wall plates 23 and 24 rest upon the upwardly projecting edges of the bottom frame 20, the latter being received between corresponding angle closure members 27 and 28 comprising, respectively, the lower edge of said wall plates. Each wall plate is provided interiorly with a vertical channel 29 extending to the bottom thereof in which are engaged opposite edges of an intermediate partition 30 constituting a wall dividing the air conditioning unit into two substantially equal areas. The bottom edge of partition 30 fits in the transverse angle member 22 of the bottom frame and the upper edge is notched at opposite corners 31 to accommodate beads 32 at the top edges of walls 23 and 24. The upper corners of front and back walls 23 and 24 are rounded so that said top edges are closely engaged by a top plate 33 constituting a combined cover and duct support for the unit. The cover plate 33 is a substantially rectangular sheet metal member, the opposite ends of which are curved downwardly to present an ornamental appearance suggestive of stream lining, each end extending downwardly along the sides of the cabinet below the termination of the curvature to engage upper edges of end plates 25 and 26. End plates 25 and 26 extend vertically from the cover plate 33 to the floor, each including horizontal brackets 34 for supporting a pair of locking members 35. Locking members 35 are pivoted in brackets 34 and operable from the exterior for locking or disengaging operation with respect to the end angle members of the bottom frame 20. It will be understood that the elements described are assembled to form a dust-proof and substantially air-tight casing when incorporated into the system with elements to be described hereinafter.

The cabinet described above constitutes a casing for a restricted U-shaped air conditioning area, a descending column of air entering via rectangular inlet aperture 36 and an exhaust column ascending therefrom through opposed aperture 37 cut in the cover plate 33. In order to provide communication in the air-conditioning area between the apertures 36 and 37, a rectangular transverse aperture 38 is formed at the lower end of the partition 30. It will be evident that the descending column entering aperture 36 will pass downwardly through treatment chamber 39 therebeneath, pass through the transverse aperture 38 and move upwardly through heating chamber 40 on the opposite side of the partition and through exhaust aperture 37.

The dimensions of the casing may vary with

the size of the installation; however, it will be observed that the construction described is one form capable of accommodating without essential modification a considerable variety of air conditioning accessories and respective capacities without necessitating alteration. For example, it will be observed by reference to Fig. 9 that the front and back plates 23 and 24 may be utilized in many instances whether or not the width of end plates 25 and 26 are modified and vice versa. The bottom frame 20 and cover plate 33 are perfectly adapted for utility regardless of the height of the installation. The entire assembly is composed of sheet metal and stiffening angle members, making for a light and attractive-appearing casing while at the same time affording convenient provision for rigidity, durability, and convenient handling in assembly and modification.

The system contemplates the provision of mechanically derived pressure for transmission of the air through the building, such pressure being obtained by operation of a blower 41 mounted in the bottom of the treatment chamber 39. Blower 41 is of the cylindrical type, disposed for horizontal delivery through transverse aperture 38 and driven by any suitable type of noiseless motor 42. Both blower and motor are fixed on a horizontal support plate 43 resiliently supported on the floor and maintained in proper location with respect to the treatment chamber 39 by spacing bars 44 fixed in the frame 20. The motor 42 is equipped with cable 45 extending to any suitable outlet (not shown) for power supply. The fan or blower 41 is relatively large to provide ample pressure at low, quiet speed and by mounting it with motor 42 on the resiliently supported plate 43 any vibration incident to its operation is absorbed and prevented from being transmitted to the casing, ducts, or any other parts of the system.

The treatment chamber 39 receives the return air to be conditioned and is designed to include, in addition to the blower 41, filtering and refrigerating apparatus 46 and 47, respectively. The filtering apparatus is preferably of the viscous type incorporated in a rectangular frame or tray 48 and consisting of a porous layer of material such as metal shavings, glass wool, and the like, coated with a viscous substance such as oil held between layers of expanded metal (not shown). Important features of the invention include the disposition of the filter perpendicularly and substantially entirely across the U-shaped air stream and the inclusion in the cabinet structure of especially located and designed mountings which not only enable compact disposal in the cabinet but also the convenient removal of the filter 48 upon occasion of periodic replacement or inspection. By disposing the filter entirely across the treatment chamber perpendicular to the U-shaped air stream initially upon its reception in the unit, full cleansing treatment is assured, thus obviating frequent cleaning of the other instrumentalities of the system. The filter tray 48 is detachably mounted in the described relation on angle bars 49 preferably of metal which are secured horizontally across the walls of the chamber 39 below the plane of the cover plate 33. The angle bars are preferably welded or otherwise suitably affixed to the stiffening angle members of the front and back walls 23 and 24, and movement of the tray by sliding therealong is readily accomplished.

When the system is utilized for cooling, re-

refrigerating apparatus 47 is placed in operation. Refrigerating apparatus 47 consists of upper and lower-inter-connected cooling plates 58 comprising a cooling unit mounted in opposite sheet metal saddles 51. The saddles 51 are indirectly supported by angle bars 52 welded or otherwise suitably secured to the vertical frame members of the cabinet in order to permit horizontal sliding of the cooling plates during inspection and adjustment therein. It will be noticed that the angle bars 52 and saddles 51 are disposed perpendicular to the descending column of filtered air and that they extend substantially entirely thereacross whereby maximum cooling is obtained. Angle bars 52 disposed immediately below and corresponding with angle bars 52 act as horizontal supports for a de-humidifying tray 54, tray 54 being rectangular in shape to correspond with the cross-section of the descending column of air and having lateral saddles 55 fast thereto for sliding engagement and support in angle bars 52. The cooling plates 58 are connected by cooling pipes 56; and an expansion valve 57 is interposed in pipe 56 communicating with any suitable source of liquid refrigerant (not shown) which may be remotely located in any convenient position. It will be understood that by remotely locating the compressor, not only is the heat incident to its operation eliminated from the air conditioning system, but screening or concealment of the compressor is facilitated. In employing the invention, an air cooled type of compressor affords economical, efficient, and silent operation. Horizontal angle spacing bar 59 is affixed to suitable brackets 60 to buttress the front and back plates 23 and 24 bearing the weight of the filtering, refrigerating, and de-humidifying equipment suspended thereon.

From the foregoing it will be observed that the descending column of air is entirely subjected successively to complete filtering, cooling, and de-humidifying in treatment chamber 39 in order that the air propelled by blower 46 will be completely air conditioned for re-circulation through the conduit system.

One of the more important aspects of the invention is the provision of a sectional heating unit 61, shown in detail in Figs. 3 to 8, which may be composed of any desired number of sections 62, each composed of corresponding cast half sections 63. Each half section 63 includes a continuous rim 64 formed at the bottom to define the exterior of a fire box 65 and diverging thereabove on each side to enclose a heat exchanger portion 66. The lower portion of the casting is recessed at 67 to provide space for the fire box 65 which extends longitudinally of the heating unit. The casting includes an integral transverse web portion 68 extending between opposite portions of rim 64. Midway between the sides the upper portion of the casting is formed with a circular aperture 69 surrounded by an integral annular projection 70, extending from web 68 in a direction opposite the rim 64.

Each section of the heating unit is composed of two of the half sections 63 assembled by butt-welding along the respective rims 64 to produce a flat hollow body, the interior of which forms a continuous passage connecting the fire box 65 and the circular aperture 69 constituting a passageway for hot gases of combustion originating in the fire box. The interior face of each half section 63 is formed with integral projecting baffle plates 71 arranged in three directions. The

lowermost group 72 consists of a plurality extending diagonally above the fire box recess 67. These diagonal baffle plates constitute guides for directing the gases of combustion upwardly and divergently across the expanse of the heat exchanger and in contact with a second group of plates 73 which are arranged in a plurality of horizontal rows one above the other individually and in staggered relationship to insure that the gases directed thereupon will be forced through a highly tortuous path of a variable character thereby insuring retention of the gases in contact therewith for a relatively long period of time to warrant maximum heat absorption therefrom. Above the horizontal bank of baffles 73 a plurality of baffles 74 diagonally disposed further impede the progress of the hot gases of combustion toward the circular flue aperture 69, thereby contributing in retaining the hot gases within the section until important heat thereof is entirely surrounded.

The annular projection 70 on the external face of each half section not only acts as an exhaust flue for gases but it projects beyond the web portion 68 and serves additionally as a spacing means for the adjacent heat exchange sections in the unit. The lower portion of the half section includes an integral extended wall 75 of continuous character which extends around the bottom of the fire box 65 and tapers inwardly thereabove to define the upper extent of combustion chamber 70. It will be observed by reference to Figs. 3 and 6 that the wall 75 and annular projection 70 extend to the same vertical plane and cooperate in spacing adjacent heating sections of the unit with respect each to the other. Externally the web 68 is formed with a plurality of integral heat exchange fins 77 disposed to project therefrom into the surrounding air stream. It will be observed that the fins 77 are especially designed and arranged to provide highly effective heat exchange, in that they are wide and thin, terminating in a straight edge 78 and are disposed in stream lined alignment. The web portions of the respective heat exchange sections are spaced each from the other by the projections 70 and 75 in order to permit circulation of air between the sections, and the fins 77 extend deeply into the air stream for maximum heat exchange due to radiation, convection, and conduction.

Projecting laterally on opposite sides of the wall 75 and at the top and bottom of the half sections 63 are corresponding lugs 79 bored to accommodate draw bars 80 for assembling the plurality of sections 62 to form a heating unit of the desired capacity. The sections are assembled in air-tight relationship to form a continuous heater, as shown in Fig. 6, the edges of annular projections 70 and walls 75 being tapered for reception with any asbestos gasket in continuous sealing rings 81 and 82 disposed between adjacent projections 70 and walls 75, respectively.

The heating unit may be composed of any number of sections 62 depending upon the heat production and exchange capacity requisite to supply the requirements of the integrated system. Although the present disclosure in the main suggests an installation involving three sections 62 to form a heating unit, it should be understood that any number of sections, for example, from one to five, may be assembled to correspond with the requirements of ordinary installations, and that the system disclosed readily may be integrated.

grated for utilization of more than five such sections.

When the three sections 62 have been assembled in sealing rings 81 and 82 the forward section 62 is provided with top and bottom closure plates 83 and 84, respectively. Top closure plate 83 includes a flat disk with a peripheral flange 85 projecting on one face thereof. Flange 85 is formed with a continuous groove for receiving an asbestos gasket and the forward edge of flue projection 78. Bottom plate 84 is provided on one face with a peripheral grooved flange 86 in which is received on an asbestos gasket the projecting wall 75 of the immediate section 62. The rearmost section 62 is provided at the top with a tubular fitting 87 for connection with a stack or other suitable flue exhaust (not shown), one edge thereof being formed with a continuous groove 88 in which is received edge 78 of the immediate section. A lower rear plate 89, also on suitable asbestos packing, is of standard design and includes a forwardly extending continuous rim 90. The rim has a continuous groove 91 in which is received the rearwardly extending wall 75 of the section 62. In order that the closure elements may be assembled in air-tight connection with the main section elements, the former are provided with integral lugs 92 bored to receive draw bars 93. To insure a relatively rigid air-tight assembly of the heating unit, nuts 94 for tightening on draw bars 88 and 93 seat on spring washers 95 in all connections whereby allowance is made for expansion and contraction due to temperature changes.

The rear closure plate 89 constitutes a rearward extension for the combustion chamber and is designed for the reception of various of the fittings requisite for heating. For example, a recess 96 serves as an observation opening, same being surrounded by a flange 97 for the reception of a door 98. Immediately below the observation opening a recess 99 is provided which is adapted to be closed by a pivotally suspended mounting plate 100. Mounting plate 100 is formed with a central recess 101 for receiving draft tube 102 of any suitable type of oil or gas burner 103. Spaced between the front and rear closure plates of the unit by an envelope of asbestos fill 104 topped in the usual manner with hearth cement 105 is fire pot lining 106 composed of pre-cast refractory sections 107, 108, and 109. Front section 107 is rectangular substantially to correspond with the interior dimension of the cast portion 67 while the middle section is U-shaped and cemented as a spacer to connect the front section with rear section 109. Rear section 109 is formed with a recess 110 in which is cemented the oil burner draft tube 102 to position the burner in its proper location in the fire box 65. By reference to Fig. 6 it will be noted that the fire box is assembled rearwardly of the median line of the heating unit in order to facilitate the even distribution of heat in the combustion chamber and over the flue baffles and compensate for the forward draft of the oil burner. Above the asbestos fill and fire box the combustion chamber extends from the front closure plate toward the rear closure plate to include a hinged heat deflector 111 pivotally suspended from the top of the rear closure plate to prevent the rear closure plate from becoming heated. Hinged heat deflector 111 is formed with a sight opening 112 in alignment with the observation opening 96 for permitting inspection of the combustion chamber therethrough during operation.

The heating unit described is spaced from the floor of the cabinet by vertical pipe legs 113 mounted in floor-engaging flanged disks 114, the upper ends of said pipe legs receiving lugs 115 cast integrally on the lower surface of the heating sections. Spacing of the heating unit from the floor is an important feature in that it enables the conditioned air blown from treatment chamber 39 to pass thereunder in order that half thereof will advance on either side of the heating unit. To facilitate equal distribution of air on either side, the cabinet is provided with a curved guide plate 116 fast to the partition 38 and extending across the transverse aperture 38. Guide plate 116 is curved upwardly to direct one-half the air stream to the right of the heating unit, the other half flowing under said unit to the left side thereof.

By reference to Fig. 7, for example, it will be noted that the cabinet is designed to envelop the heating unit closely, sufficient clearance being provided at the front and sides of the heating unit to enable flow of air thereacross; such spacing, however, being designed to maintain the air stream in relatively close contact with the exterior of the heating unit in order to promote heat exchange and derive compactness. The movement of the lower portion of the stream along the left side of the unit is directed by a curved guide plate 117 fast to the wall of the cabinet and extending downwardly to engage the floor at the left of the heating unit.

The rear wall 24 of the cabinet is cut out as shown at 118 and 119 to enable it to fit over the flue exhaust fitting 81 and rear closure plate 89, respectively, of the unit, in order to save space and permit access in connection with the sight opening and burner without removal of the rear wall of the cabinet. Continuous packing rings 120 and 121 surround the recesses 118 and 119 for maintaining the recess edges in air-tight connection with continuous asbestos gasket seals 122 and 123, respectively, for preventing escape of air from the cabinet.

From the foregoing it will be observed that the air heated in the fire box 65 flows from the combustion chamber through the several hollow heater sections 62 and outwardly therefrom through the exhaust fittings 81. Very little heat, however, is lost in the flue gases due to their prolonged contact with the baffles 71 defining the tortuous passages between the combustion chamber and the flue. By employing a silent type burner, the heating unit operates quietly; any slight noise being effectively muffled by the enveloping cabinet. The conditioned air delivered through the transverse opening 38 proceeds along the successive elongated surface of the heat exchange fins which, being disposed in stream lined fashion, conform to the direction of flow of the stream for frequent and prolonged heating contact therewith without producing swirls or eddies and concomitant noise.

The curved guide plates within the heating chamber of the unit 12 direct the air stream from the blower across the bottom of the unit and upwardly therethrough to the supply conduit without swirls or pocket eddies at the angles of the cabinet, thereby eliminating an important source of transmission noise.

Economical heating is a function of efficient heat exchange and relatively high exchange values are obtainable by suitable baffle arrangements which maintain the air to be heated in contact with the hot surface as long as possible.

Prior constructions, however, are frequently unsuited for incorporation in a modern air conditioning system in that, among other reasons, the requisite swirling of the air and retention in contact with external projections produces eddy currents and additional friction load on the transmission system. This must be compensated for by increased fan speed and this, in turn, is productive of more objectionable noise. In the present invention, efficient heat exchange is obtained without noise by causing the hot gases of the combustion chamber to be propelled along a highly tortuous path defined by the multiplicity of baffles lying in staggered relationship inside of the heat exchange sections. This insures maximum absorption of the heat supplied, any resulting noise being confined within the cast iron heat exchanger and thereby effectively muffled. The air flows over the exterior of the heat exchangers without possibility of noisy swirling due to the stream lined disposition of the multiple extended heat exchange fins distributed over the exteriors thereof. The combination of the described internal baffles and external stream lined fins, therefore, enables maximum heat exchange with a minimum load on the blower, thus insuring noiseless operation with economical heating.

Suitable apparatus (not shown) may be provided, preferably in the top of the cabinet, for humidifying the heated air. Suitable controls (not shown) which form no essential part of the present invention are, of course, provided for the measured operation of the various instrumentalities in the system. The cabinet is provided with beads 124 and 125 surrounding the supply and exhaust openings 36 and 37, respectively, in the top cover plate for the convenient and close-fitting reception of standardized terminal conduit sections 126 and 127, respectively, communicating with the opposite sides of the conduit system.

An alternative form of heat exchanger construction is shown in Fig. 8. Therein the integral cast baffles 71 on the half section 63 are arranged much more closely together and in greater number than in the embodiment shown in Fig. 7. This usage is preferable under certain conditions, as for instance in gas firing, in order to compensate for greater tendency for slippage and loss incident to such method of heating. It will, however, be observed that the design of the individual baffles and the plan of distribution in the sections, as in the former case, is contrived to promote extremely high heat exchange through requiring passage of the hot gases of combustion through a tortuous path before permitting egress through the flue fitting 87.

The attractiveness, compactness, and efficiency of the air conditioning unit described may be obtained without sacrifice of any desirable household equipment; for example, the sectional heating unit and enveloping cabinet are adapted to accommodate any suitable type of hot water coil 128 leading to a storage tank (not shown). The coil 128 is mounted by recessing the rear cover plate 89 at 129 and hinged heat deflector 111 at 130. Any suitable fitting 131 rigidly mounts the coil on the rear cover plate so that it extends across the upper portion of the combustion chamber to receive maximum heating effect from the hot gases therein. Mounting the heating coil directly through the rear cover plate obviates interference with the flow of conditioned air between the cabinet and heat exchange surfaces of the unit; and its dis-

posal within the combustion chamber beneath the baffle passages thereof enhances the impeding effect on the gases of combustion and assisting in prolonging their contact with the heat absorbing baffles.

Fig. 10 discloses an assembly illustrating the adaptability and elasticity of the integrated standardized sectional air conditioning system disclosed. Therein will be observed the organization of the air conditioner and cabinet when the heating unit is composed of less than three sections. For example, if two sections constitute the heating unit they may be positioned to extend transversely of the heating side, so that the heater front faces the central, the rear cover plate and rear appliance fittings extending laterally toward the left. In the specific embodiment presented, apertures 132 and 133 are formed in side plate 134 for the reception of an exhaust fitting 135 and rear cover plate 136, suitable finishing rings 137 and 138, respectively, being attached thereto for preventing escape of the conditioned air therefrom. In this relation the other half of the cabinet may be equipped with the requisite complement of air conditioning instrumentalities described. Connection in the conduits for recirculation and re-conditioning of the air is effectuated, as in the manner described above, through opposite inlet and exhaust apertures 139 and 140, respectively.

Regardless of the size of the installation and the consequent number of sections constituting the heating unit, the constructions described are especially designed to obviate any necessity for dismantling the cabinet and contents during the life of the burner. As pointed out above, accumulation of dust within the cabinet is prevented by filtering the air stream immediately upon its entrance. When the pre-fabricated cabinet is assembled in situ, the various elements thereof are connected to preclude entrance of dust at any of the joints.

The interiors of the various heat exchanger sections are adapted to be easily cleaned by brush or air pressure, a cleaning aperture 141 being provided at the outer side of each section. Cleaning aperture 141 is preferably rectangular, being defined by integral bosses 142 in the horizontal plane of the cabinet end plate 26. Inner face 143 of rectangular closure plate 144 (Fig. 4) receives the boss 142 to provide an air tight closure. Perforated lugs 145 on the plate enable the demountable bolting of the plate to close the clean out aperture 141 during heating operation. Cleaning the interior of the heating section requires merely the temporary removal of cabinet end plate 26 and removal of the closure plate 144, both plates being easily removed and replaced without interfering with other portions of the apparatus.

I claim:

An air heating furnace having means defining an enclosed air heating space, means to admit cold air to said space, means to direct heated air from said space and a heating unit within said space, said unit comprising a plurality of similar sections each formed to define a combustion chamber portion, a flue portion above said combustion chamber portion and an outwardly flared hollow means defining a continuous enclosed space of substantially greater width than the combustion chamber portion communicating with each of said portions, said hollow means being defined by parallel side walls of a width substantially greater than the width of

the combustion chamber portion and relatively narrow end walls flared outwardly, the said side walls constituting heat exchange surfaces to bring air in indirect heat exchange relationship with hot gases of combustion over a surface substantially wider than the combustion chamber portion, said sections being connected in side-by-side relationship, integral air directing means projecting from the external surface of each of 10 said sections arranged to promote contact of air

to be heated with the whole of said external surface and direct said air toward the lower side of said flue portion and integral gas directing means projecting from the internal surface of each of said sections arranged to promote contact of combustion gases from said combustion chamber portion with the whole of said internal surface in the flow of said gases from said combustion chamber portion to said flue portion. 5

May 23, 1939.

ALLEN P. LIVAR.

It is hereby certified that error appears in the printed specification of the above numbered patent requiring correction as follows: Page 3, second column, line 21, for the word "surrounded" read surrendered; and that the said Letters Patent should be read with this correction therein that the same may conform to the record of the case in the Patent Office.

Signed and sealed this 25th day of July, A. D. 1939.

(Seal)

Henry Van Arsdale,
Acting Commissioner of Patents.
